US00D879068S

(12) **United States Design Patent** (10) Patent No.: **US D879,068 S**
(45) Date of Patent: **** Mar. 24, 2020**

(54) **WIRELESS HEADSET**

(71) Applicant: **Xiaohuang Yan**, Fuzhou (CN)
(72) Inventor: **Xiaohuang Yan**, Fuzhou (CN)
(**) Term: **15 Years**
(21) Appl. No.: **29/653,950**
(22) Filed: **Jun. 20, 2018**
(51) LOC (12) Cl. **14-01**
(52) U.S. Cl.
USPC **D14/206**; D14/226
(58) **Field of Classification Search**

CLAIM

The ornamental design for a wireless headset, as shown and described.

DESCRIPTION

FIG. 1 is a perspective view of a wireless headset, showing my new design;

FIG. 2 is a front view thereof;

FIG. 3 is a rear view thereof;

FIG. 4 is a left-side view thereof;

FIG. 5 is a right-side view thereof;

FIG. 6 is a top view thereof; and,

FIG. 7 is a bottom view thereof.
